CLAIM

We claim the ornamental design for the sprayer plumbing layout, as shown and described.

DESCRIPTION

FIG. 1 is a top right perspective view of the sprayer plumbing layout showing our new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.

The broken line showing in FIGS. 1–7 is included for the purpose of illustrating portions of the sprayer plumbing layout and forms no part of the claimed design.
